UNITED STATES PATENT OFFICE.

ERNST WEILER, OF BERLIN, GERMANY.

VEHICLE-WHEEL RIM.

No. 805,828.

Specification of Letters Patent.

Patented Nov. 28, 1905.

Application filed March 7, 1905. Serial No. 248,833.

To all whom it may concern:

Be it known that I, ERNST WEILER, manufacturer, of Berlin, in the Kingdom of Prussia, German Empire, have invented certain 5 new and useful Improvements in and Relating to Vehicle-Wheel Rims or Fellies, of which the following is a specification.

Wheel rims or fellies consisting of a number of parts adapted to be screwed together 10 by means of continuous screw-threads are already known; likewise constructions in which the rim halves or members are adapted to be assembled by means of oblique slots and pins or by means of a helically-arranged 15 bead or protuberance and with the help of set-screws. These wheel-rims, however, lack the characteristic of the rim which forms the subject of the present invention, which consists in the fact that during the assemblage of 20 the rim members these latter, in addition to an automatic centering, are only actually held upon the meeting of conical or wedge shaped abutting edges.

The construction which forms the subject 25 of this invention is illustrated in the accompanying drawings, in which—

Figure 1 shows a portion of the rim in front elevation with the edge removed. Fig. 2 is a side elevation. Fig. 3 is a side elevation, partly in section. Fig. 4 is a cross-section; and Figs. 5 to 15, inclusive, are views in cross-section of various modifications of the structure shown in the preceding figures, 35 showing only a portion of the felly and of the removable tire-securing rim in position thereon.

This construction is characterized by the fact that the two rim members are provided with wedge-like ribs *a*, either separate 40 one from the other or overlapping, so that after the application of the ring with the screw-threads rotation through a very small angle is sufficient for obtaining a certain connection. In order to obtain during the attachment of the flange on the rim a mutual centering and thereupon a rigid and secure connection between the two assembled rim members, the outer edge of the rim-periphery is chamfered so that only upon the 45 fixing of the correspondingly-chamfered inner edge of the rim-flange which is to be attached is a completely-rigid assemblage produced. The automatic centering is further facilitated owing to the fact that between the separate 50 ribs *a* effecting the fixing a certain amount of play or space is left, which permits of rela-

tive displacement of the two parts, if required, and also assists the firm assemblage of the chamfered faces *b* on the abutting edges.

The principle of the conical faces *b* may be utilized in numerous constructions. Figs. 4 to 15 show various arrangements of this kind. It is not only a question of the form of the wedge-like ribs, but also of the centering and the joint between the rim and the abutting edge forming the detachable rim-crown. As shown in Figs. 14 and 15, by way of example, the rim edge may also advantageously be constructed in two separate 70 parts, one of them being formed as a smooth rim edge to be passed over the rim, while the second part, which is crown-like and provided with the ribs referred to, is intended in being united to the rim to center the 75 smooth rim edge which has been previously placed in position and to press against the rubber tire. It will of course be understood that in the case of this separate crown-shaped part also all the different wedge-rib forms and 80 also the various formations of its abutting edge may be employed. By means of these oblique faces *b* not only is an automatic centering obtained, but also a perfect joint between the two assembled rim members, 85 which is the better insured if before the assemblage they are coated with a solid lubricant, which prevents moisture, dust, and dirt from entering the rim. The perfect junction might also be obtained by forming 90 on both the edges coming into contact a small groove serving for the reception of a packing-strip of some suitable material.

Having explained the nature of my invention and described forms of constructing and the manner of using the same, what I claim, 95 and desire to secure by Letters Patent, is—

1. A wheel rim or felly in two parts, comprising a detachable ring or flange in which the ring and the outer edge of the rim carry helically-formed ribs bearing mutilated screws engaging one with the other and a tire-engaging flange on each part by which the tire is wedged into and held firmly in position when the parts are screwed together.
2. In a device of the class described, a dismountable outer wheel-rim combined with an inner rim in which wedge ribs on each form a screw engagement so formed as to hook one within the other, so that they present conical pairs of wedge faces parallel with each other, by means of which the cen-

- tering and joint formation between the two assembled parts is simultaneously obtained, and a flange on the wheel-rim, and on the inner rim, between which the tire is held.
- 5 3. In a device of the class described, a wheel felly or member having a flange on one side adapted to engage the securing edge of a rubber tire, a mutilated or non-continuous screw-thread formed upon the unflanged edge of the felly, and an annular like threaded and flanged member adapted to engage with the felly to secure the tire in place.
4. In a device of the class described, a wheel felly or member having a flange on 15 one side adapted to engage the securing edge of a rubber tire, a mutilated or non-continuous screw-thread formed upon the unflanged edge of the felly, an annular like threaded and flanged member adapted to engage with 20 the felly to secure the tire in place, and a packing-gasket of elastic material interposed between the two screw-threaded parts.
5. In a device of the class described, a wheel-rim having a flange for securing one side of the elastic tire and an annular member with a coacting flange fitted to the wheel-rim by means of a wedging bayonet-joint. 25
6. In a device of the class described, a wheel-rim having a flange for securing one side of the elastic tire, and an annular member with a coacting flange fitted to the wheel-rim by means of a wedging interrupted screw-joint. 30

In witness whereof I have hereunto signed my name this 9th day of January, 1905, in the presence of two subscribing witnesses.

ERNST WEILER.
